UNITED STATES PATENT OFFICE

WILLIAM B. STOUT, OF DETROIT, MICHIGAN

DESIGN FOR AN AIRPLANE

Application filed May 11, 1931. Serial No. 39,815. Term of patent 14 years.

To all whom it may concern:

Be it known that I, WILLIAM B. STOUT, a citizen of the United States, residing at Detroit, in the county of Wayne and State of Michigan, have invented a new, original, and ornamental Design for Airplanes, of which the following is a specification, reference being had to the accompanying drawings, forming part thereof.

Fig. 1 is a side elevation, Fig. 2 is a front elevation and Fig. 3 is a plan view of an airplane, showing my new design.

I claim:

The ornamental design for an airplane, as shown.

WILLIAM B. STOUT.
